MAGNETICALLY BIASED TELEPHONE
RINGER

Louis W. Carroll, New York, N. Y., assignor to International Standard Electric Corporation, New York, N. Y., a corporation of Delaware

Application August 4, 1942, Serial No. 453,516

3 Claims. (Cl. 177—7)

This invention relates to new and useful improvements in ringers and more particularly in biased electro-magnetic ringers such as are used on telephone party lines where it is required to ring a station only when current flows in the circuit in a given direction.

The object of the invention is to eliminate the customary adjustable springs or other mechanical means for securing biased operation.

I shall describe a preferred embodiment of the invention in connection with the drawing which represents the improved ringer in side elevation.

1 and 1' are the customary two electro-magnets having pole pieces and coils supported by a yoke 2. A permanent magnet 3 is fastened to the yoke 2 centrally between the two magnets. The longitudinal axis of the permanent magnet 3 is at the center of yoke 2 midway between the longitudinal axes of the two electro-magnets. The pole at the upper free end of the permanent magnet 3 projects to a point above the pole pieces of the two electro-magnets. By means of rivets 6, a fork 5 having two bearing or pivot points 4 (only one being shown) is fastened to the side of magnet 3. The bearing points 4 are to the right of the central axis of the electro-magnet structure and almost in line with the edge of the coil of magnet 1'. Armature 8 is pivotally supported between the bearings 4. The armature is symmetrically positioned with respect to the magnet structure and, therefore, its pivot point is to the right of its center which is in alignment with the permanent magnet 3 and where a clapper-arm 7 is attached. The armature is provided with the usual stop pin 9 near one end cooperating with the pole piece of magnet 1' and an adjustable stop screw at the other end cooperating with the pole piece of magnet 1.

The pole of the permanent magnet 3 is just below the lower surface of the armature 8 in alignment with the center thereof. This permanent magnet pole will pull the longer left-hand leg of the armature down until the stop-screw 10 hits against the pole piece of magnet 1'. This magnetic pull supplies the biasing effect that is customarily produced by a biasing spring or the like and holds the magnet armature in the position desired until it is overcome by current through the coil of magnet 1' in the proper direction. Pulsating current flowing through the two

coils will cause the armature to oscillate and the clapper-arm 7 to hit the gongs 11.

What I claim is:

1. In a biased electro-magnetic ringer, two electro-magnets, a permanent magnet, means for supporting the magnets, an armature cooperating with said magnets and having its center aligned with the permanent magnet and adjacent to one pole thereof a magnetic connection between the other pole and said electro-magnets, a pivotal mounting for said armature engaging it at a point between its center and one end, and a clapper-arm attached to the armature at its center.

2. In a biased electro-magnetic ringer, two like electro-magnets having coils and pole pieces, a yoke on which said magnets are mounted spaced from one another, a permanent magnet of the bar type, one pole of which is attached to said yoke between the coils of said magnets, an armature cooperating with the free pole pieces of said permanent and electro-magnets, the center of said armature being aligned with said permanent magnet, a pivotal support for said armature fastened to the side of the permanent magnet and engaging the armature at a point between its center and one end, and a clapper-arm attached to the armature at its center.

3. In a biased electro-magnetic ringer, two like electro-magnets having coils and projecting pole pieces, a yoke on which said magnets are mounted spaced from one another, a permanent magnet of the bar type, one pole of which is attached to said yoke centrally between the coils of said magnets and the other pole of which projects to a point above the pole pieces of the electro-magnets, an armature above the last mentioned poles and in cooperative relationship therewith, the center of the armature being aligned with the permanent magnet and the ends with the said two electro-magnets, a pivotal support for said armature fastened to the side of the permanent magnet near the free pole thereof and engaging the armature at a point between its center and one end, a stop pin near one end of the armature cooperating with the pole piece of one electro-magnet, an adjustable stop screw near the other end of the armature cooperating with the pole piece of the other electro-magnet, and a clapper-arm attached to the armature at its center.
